CLAIM

The ornamental design for a luggage panel, as shown and described.

DESCRIPTION

FIG. 1 is a front elevation view of the luggage panel of the present invention showing the Applicant's new design; FIG. 2 is a back elevation view of the luggage panel of FIG. 1;

FIG. 3 is a right side view of the luggage panel of FIG. 1; FIG. 4 is a left side view of the luggage panel of FIG. 1; FIG. 5 is a top plan view of the luggage panel of FIG. 1; and, FIG. 6 is a bottom plan view of the luggage panel of FIG. 1.

The broken lines showing the strap are for the purposes of illustrating environment and form no part of the claimed design.
